UNITED STATES PATENT OFFICE.

CHARLES SIGFRID LENZ AND GEORGE EDWARD JUPP, OF NEW YORK, N. Y., AS-SIGNORS, BY MESNE ASSIGNMENTS, TO AMERICAN MARINE DEVICE CORPORATION, OF NEW YORK, N. Y., A CORPORATION OF NEW YORK.

APPARATUS FOR SEPARATING LIQUIDS OF DIFFERENT SPECIFIC GRAVITIES AND INDICATING MEANS THEREFOR.

Application filed May 9, 1923. Serial No. 637,734.

To all whom it may concern:

Be it known that we, CHARLES S. LENZ and GEORGE E. JUPP, citizens of the United States, and residents of the city of New York, borough of Manhattan, in the county and State of New York, have invented a new and Improved Apparatus for Separating Liquids of Different Specific Gravities and Indicating Means Therefor, of which the following is a full, clear, and exact description.

This invention relates to an apparatus for separating liquids of different specific gravities, such as oil and water, and to automatic indicating means therefor.

An object of the invention is to provide a simple and efficient apparatus which can be installed for use especially on board vessels for the automatic separation of, preferably, oil and water, so that the water may be pumped overboard and the pumping cease the instant the level of oil is reached, and the oil will not be pumped overboard.

Another object concerns the provision of means whereby a signal will automatically be given when the pumps have finished pumping the water and have reached the oil, so that the entire pumping operation can be stopped.

A further object concerns the provision of means whereby in the separation of liquids of different densities and different specific gravities and, consequently, having different degrees of viscosity, means are provided whereby in the pumping of one liquid the rate of operation of the pumping mechanism is affected the instant a liquid of different viscosity is acted on by the pumps in such manner as to cause the cessation of the pumping operation.

The invention is illustrated in the drawings, of which—

Figure 1 is a sectional view taken through the hull of a boat showing one form of my apparatus;

Fig. 2 is a detail section of the speed controlled means for shutting off the power to the pump and for giving a signal;

Fig. 3 is a section through a modified form of the apparatus;

Fig. 4 is a detail view of the liquid-flow check chamber;

Fig. 5 is a horizontal section through said chamber; and

Fig. 6 is a circuit diagram of a modified form of an indicating and alarm device. 55

The forms of the invention shown in the drawings are preferred forms, although it is understood that modifications in the constructions and arrangement of the parts and in the character of the materials used 60 may be adopted without departing from the spirit of the invention.

This invention is intended primarily for use on shipboard where in recent years the use of liquid fuel such as oil has come substantially into use. On board, the boats a considerable quantity of oil gets mixed with the bilge water, and since this water is being constantly discharged overboard by the pumps it is highly objectionable when this 70 action takes place near the shore, and especially in harbors and ports of call. Therefore, the various countries are requiring that means be provided for separating the oil, or at least means provided for preventing 75 the discharge of the oil overboard. It is, of course, necessary that any such means should be as fully automatic as possible in view of the fact that it must be in operation practically all of the time and, therefore, the less attention and repair that is required the more desirable it is. 80

In addition, it often happens that water gets mixed with the fuel oil in the fuel tanks, and if water gets in these tanks to 85 any considerable extent and is fed to the burners of the vessel's boilers, it is liable to create a dangerous flare-back, which might result in loss of life in the fire room. Therefore, it is necessary to separate the oil 90 and the water for these two and very important reasons, if not for others.

We, therefore, provide apparatus which includes pumping mechanism connected to the tanks containing the oil and water and 95 which when started in operation will commence to pump the water. This apparatus is so designed that for its operation when pumping on water the various elements of the apparatus are in normal condition. 100 However, the pumping apparatus is supplied with a controlling mechanism the position of which is determined by the speed of the pumps and the rate of operation thereof, and, therefore, when the pumps 105 commence to work on the heavier oil, which

is more viscous than the water, this speed controlling apparatus varies its position and in so doing is connected to other controlling apparatus, such as valves, whereby the operating fluid, such as steam, leading to the pumping mechanism can be closed to shut down the pumps and, therefore, prevent the further pumping of oil.

In the more specific construction of the invention, which comprises a main pumping apparatus leading to one or more tanks liable to contain two different fluids and including a control valve whereby the power fuel to said pump is regulated, this control valve is connected to a speed controlled mechanism such as a centrifugal ball governor, and this governor is in turn connected or associated in some suitable manner with an auxiliary or detector pump mechanism which is preferably operated by a motor, this detector pump being connected to a point near the bottom of the tanks at a slightly higher level than the pipe leading from the main pump. When the auxiliary or detector pump is started it will pump water, and as long as it is pumping water the speed of the auxiliary or detector pump will be fairly uniform, whereby the position of the centrifugal controlling device will be maintained in a substantially uniform position. In this position the valve controlled thereby and regulating the flow of power fuel to the main pump will be open. However, as soon as the oil level is reduced so that the detector pump commences to pump oil, its speed will slacken or vary so that the position of the governor balls will vary, and this variation will cause the main power fuel valve and the main pump to be closed, shutting off said pump. The difference in the level of the bottoms of the pipes leading from the detector to the main pump will permit the main pump to be shut down before it commences to pump oil. The variation in the position of the centrifugal governor can also be caused to actuate either or both an audible and a visual signal so that the detector pumping apparatus can also be closed down.

In a more specific and slightly modified form, the detector pumping apparatus can be limited to the main pumping circuit provided with a by-pass in which is located an oil-check chamber so constructed the fluids of different viscosity will flow therethrough at different rates of speed. In the main circuit will be located a vacuum apparatus connected to the main power fuel valve, but this will be so disposed and constructed that when one fluid is being pumped in the circuit the vacuum will be balanced by a suitable means, such as a spring, to keep the valve in a definite position, and when another fluid commences to be pumped a different degree

of action will be established by the different rate of motion of the pump, and this will cause the upsetting of the balance and the movement of the valve, preferably to shut off the power to the main pump, whereby the consequent flow will cease almost immediately.

As shown in Figs. 1 and 2, 10 represents the hull of a vessel in the bottom of which is disposed a tank 11, which may be one of a plurality of tanks disposed throughout the hull. This tank is adapted to hold a body of fuel 12, such as oil, which sometimes becomes mixed through one cause or another with a body of other liquid 13, such as water. It is desirable that the two liquids be separated and that the water be pumped overboard, and to this end we provide a pipe 14 extending from a manifold chamber 15 to a point near the bottom of the tank 11. This manifold is connected by a pipe 16 to a pump 17, which is preferably a steam pump, supplied through pipe 18 with a power fuel such as steam. This pipe 18 has in it a valve 19, the position of which is determined by a centrifugal speed governor 20, which in turn is connected through suitable gearing 21 to a motor 22 adapted to operate a pump 23, which is preferably known as a detector pump. This detector pump 23 is connected through a manifold 24 by a pipe 25 to a point near the bottom of the tank 11, but the bottom of the pipe 25 is disposed at slightly higher level within the tank 11 than the bottom of the pipe 14, which is the pipe leading to the main pump 17. Within the pipe 23 leading to the manifold 24 is a sight glass 26, so that the character of the liquid being pumped by the detector pump 23 can be observed. The discharge pipe 27 leads from the pump 23 to some other point in the vessel where the small amount of water being pumped by the detector pump can be discharged. A discharge pipe 28 leads overboard from the pump 17.

Referring to Fig. 2, the stem 29 on which the valve 19 is mounted is provided with a plate 30 fixed thereon. This plate 30 is adapted to engage with the ends of pivoted levers 31 and 32 which are held bearing thereagainst by springs 33 and 34. The other end of lever 31 is provided with a gear sector 35 meshing with a small pinion 36 carrying an indicator needle 37 forming part of a gage casing 38. The other end of the lever 32 is adapted to make contact and acts as a switch member to close the circuit leading through the main switch 39, battery 40 to a light 41 and a bell 42. In the full line position of the parts shown in Fig. 2 the circuit is closed and the light 41 is lit and the bell 42 is sounded, also the needle indicator 37 is in a position to indicate the pumping of oil. However, if the rate of motion of the detector pump 23 increases the balls fall

out to the dotted position and the other parts assume their dotted positions, whereby the valve 19 will be opened, the indicator needle 37 will move to the position to indicate the pumping of water, and the circuit connected to the lamp 41 will be opened so that the lamp will be extinguished and the bell 42 will stop ringing.

Through suitable connections, not shown 10 since their particular character forms no part of the invention, the motor 22 may be started, and by observing the sight glass 26 the operator can see if water is being pumped. This fact being established, the 15 pump is permitted to continue and the ball governor moves out to normal position, opening the valve 19, moving the indicator to the water position and keeping the signal circuit open. The opening of valve 19 will 20 permit steam to pass around the main pump 17 which will immediately commence to pump water in larger quantities from the tank and discharge it overboard. This will 25 reduce the level of the water, and since the oil is floating on the top of the water, the body of oil will gradually approach the bottom of the detector pipe 25; and as soon as the oil reaches the bottom of this pipe the greater viscosity of the oil will tend to slow 30 up the action of the pump 23. It will be noted that the pump 23 attacks the oil first because the bottom of pipe 25 is higher than the bottom of pipe 14. As soon as the pump 23 attacks the oil the motor 22 is slowed 35 down and this causes the speed-controlling device or ball governor to drop, whereby the valve 19 is closed, the indicator is moved to the oil position and the signal circuit is closed, because of the illumination of the 40 lamp and the sound of the bell. The operator then, immediately upon receipt of these signals, shuts off power and the motor 22 and the whole apparatus stops. The difference 45 of level between the bottoms of pipes 25 and 14 is designed to give this signal in sufficient time for the operator to close down the motor 22. When the motor is closed down, of course, both pumps stop and the oil cannot be pumped overboard.

50 Of course, it is understood that there may be a plurality of tanks such as 11 and that this apparatus may be used to separate any two liquids of different viscosity located in any part of the boat; and, in fact, this invention can be used in other places than on board vessels. It is also adapted to separate the oil and water in the bilge water of vessels. It is also very important for use in separating the oil from fuel in the fuel tanks, since on modern vessels if liquid fuel and water are fed to the boiler dangerous flare-backs are sometimes caused.

55 A modification of this idea is illustrated in Figs. 3 to 6, inclusive. In this form the invention includes a tank 50 into which a

pipe 51 extends, this tank containing a level of liquid 52 and a body of water 53. The pipe 51 connects directly to a manifold 54 which in turn is connected by a pipe 55 to a pump 56. This pump is provided with a discharge pipe 57. A valve 58 is adapted to control the flow of fluid from the pipe 51. Of course, it is understood that the manifold 54 is connected by pipes to any number of other tanks. Shunted around the valve 58 70 is a liquid circuit, including a pipe 59, oil-check chamber 60, pipe 61 and valve 62. A pipe 63 also leads from the top of the oil-check chamber to a storage tank 64.

75 Preferably located between the manifold 54 and the pump 56 is a vacuum chamber 65 having a piston 66 held in the normal position by a spring 67 and connected by a lever 68 to a valve 69 located in a pipe 70 and controlling the admission of power fluid to the pump 56. The bottom of the vacuum chamber 65 is connected to the pipe 55 leading to the pump 56, and when a definite liquid, such as water, is being pumped through the pipe 55 the action of the pump is so balanced to the strength of the spring that the lever 68 is maintained in the normal position shown and the valve 69 is held open so that the pump 56 will receive its operating fluid. In 80 the normal operation of the device which is adapted to pump water, the valves 59^a and 62 are closed and the valve 58 is open, so that the pump will pump water straight from the tank 50 and overboard. However, if the automatic detector mechanism is to be 85 put into place so that the pump will stop as soon as it commences to pump oil or other liquid than water, the valve 58 is closed and the valves 59^a and 62 are opened. This causes the water to pass through the oil-check chamber 60 before it reaches the manifold 54.

90 This liquid or oil-check chamber is a drum provided with a plurality of pipes 71 of rather small diameter so that any fluid passing therethrough will meet with considerable friction and tend to have its flow checked to some extent. This is particularly true of viscous fluids, since the resistance of the fluids will increase in proportion to the viscosity. This drum is provided with a 95 pivoted door 72 which can be swung open to permit the set of pipes to be removed, since they are mounted between plates 73 and 74 to form a compact unit which can be 100 easily removed from the drum. As long as water flows through the check drum nothing happens out of the ordinary, because the vacuum device is designed to be balanced 105 when water is flowing. However, to the extent that the liquid of different viscosities flows, the balance of the suction chamber 65 is overthrown, so that the valve 69 is 110 closed, cutting off fluid to the pump 56, which immediately stops. The parts are so 115 120 125 130

designed and the apparatus so timed that the pump will stop before oil has reached the discharge pipe 57. Of course, it is understood that this vacuum apparatus controlling the steam or power fluid valve can be disposed in any part of the system, and in Fig. 4 we show it disposed adjacent the fluid check chamber or drum.

In Fig. 6 we show a signal circuit similar to the one mentioned previously, controlled by a needle indicator 75 forming part of the usual pressure gage of the Bourdon type. This may be disposed in the fluid circuit at any desired point.

It will, therefore, be seen that we have provided a simple, durable, efficient apparatus whereby two fluids of different specific gravities can be very easily separated by an action which is substantially automatic. It will also be observed that it is substantially impossible for the undesirable liquid to be discharged from the bottom of this apparatus and, therefore, the use of this apparatus is particularly advantageous on board vessels, as the prohibition against the discharge of fluids such as oil overboard is very emphatic.

What we claim is:—

1. An apparatus for separating liquids of different specific gravities, which includes a tank containing said liquids, means for pumping one of said liquids from said tank, a valve controlling the flow of fluid, and means operated by the change in rate of pumping to close said valve when the pump begins to pump the other liquid.

2. An apparatus for separating liquids of different specific gravities, which includes a tank containing said liquids, means for pumping one of said liquids from said tank, a valve, and means controlled by the speed of the pump to close said valve when the pump slows down.

3. An apparatus for separating liquids of different specific gravities, which includes a main pump, a tank containing said liquids, a connection from said pump to the bottom of the tank, a pipe leading to said pump for the admission of power fluid thereto, a valve in said admission pipe, a detector pumping mechanism, a pipe connecting said detector pump at the bottom of the tank at a slightly higher level than the bottom of the above-mentioned pipe, and means operated by the second pump to control the position of the valve in the admission pipe leading to the first pump.

4. Apparatus for separating liquids of different specific gravities, which includes a tank containing said liquids, a pump connected with the bottom of said tank, a valve controlling the flow of power fluid to said pump, a second pumping apparatus connected to the bottom of the tank, and a centrifugal governor connected to said valve

and operated by the motion of the second pump and adapted to close said valve when the motion of the second pump slows down.

5. Apparatus for separating liquids of different specific gravities, which includes a tank containing said liquids, a pump connected with the bottom of said tank, a valve controlling the flow of power fluid to said pump, a second pumping apparatus connected to the bottom of the tank, and a centrifugal governor connected to said valve and operated by the motion of the second pump and adapted to close said valve when the motion of the second pump slows down, the level of the bottom of the pipe leading from the second pump to the bottom of the tank being higher than the level of the bottom of the pipe leading to the main pump and the bottom of the tank, whereby when the liquid of the lighter specific gravity reaches the bottom of the higher pipe the pump connected to said pipe will slow down before the other pump.

6. An apparatus for separating liquids of different specific gravities, which includes a tank containing said liquids, a pump connected to the bottom of said tank, a valve controlling the flow of fluid, means operated by the speed of the pump to determine the position of said valve, and indicating means operated by the variation of position of the speed controlled means.

7. An apparatus for separating liquids of different specific gravities, which includes a tank containing said liquids, a pump connected to the bottom of said tank, means for operating said pump, a centrifugally operated governor, a valve connected to said governor, a signal circuit, a switch in said circuit normally open, an indicating device, and means operated by the movement of the centrifugal governor to close said switch and operate said indicator whereby an indication is made and the signal circuit is established.

8. An apparatus for separating liquids of different specific gravities, which includes a tank containing said liquids, a pump connected to the bottom of said tank, a valve, and means connected to said valve and associated with the connection between the pump and the bottom of the tank to maintain the valve open during the maintenance of a definite degree of vacuum in said connection, said vacuum operated means adapted to close the valve when the vacuum in said connection increases.

9. An apparatus for separating liquids of different specific gravities, which includes a tank containing said liquids, a pump connected to the bottom of said tank, a fluid-check chamber in said connection whereby the resistance to the flow of fluid through the connection will vary in accordance with the viscosity of the liquid, a valve in said

connection, and means operated by the vacuum established in said connection to close the valve when the liquid of greater viscosity is pumped into said check chamber.

- 5 10. An apparatus for separating liquids of different specific gravities, which includes a tank containing said liquids, means for pumping one of said liquids from said tank, a connection from said pumping means to said tank, a chamber in said connection, a plurality of pipes of small diameter in said chamber adapted to form considerable resistance to the flow of fluid therein, especially fluids of considerable viscosity, a vacuum

chamber disposed in said connection, a piston 15 in said chamber, and a valve connected to said piston, the valve maintained in a definite position during the normal position of the piston, the suction of the pump increasing when the liquid of greater viscosity 20 enters the check chamber, whereby an increased suction is produced, said piston being caused to move by the increased suction, whereby the valve is closed and the operation of the pump is stopped.
